UNITED STATES PATENT OFFICE.

EUGENE SONNTAG, OF ASTORIA, NEW YORK.

WINDOW SEAT.

Application filed May 28, 1926. Serial No. 112,366.

This invention relates to window seats or chairs adapted to be detachably connected to the window frame sill in a manner to permit a person to carry out window cleaning operations.

Some of the objects of the present invention are: to provide a window seat or chair which may be detachably connected with the sill of a window frame and which will be maintained in place by a means which not only serves for securely holding the same against movement, but which also allows the same to be adjusted to the desired position; and to produce a window seat or chair of the indicated character which will be more thoroughly efficient and effectual in use for the intended purposes.

The nature of the invention and its distinguishing features and advantages will appear when the following specification is read in connection with the accompanying drawing, in which—

Figure 1 is a perspective view of the window seat embodying the present invention.

Fig. 2 is a sectional view through the window seat taken substantially on the line 2—2 of Fig. 1, and showing the window seat connected to the sill of a window frame, a portion of which is shown.

Fig. 3 is a sectional view taken on the line 3—3 of Fig. 2.

Fig. 4 is a perspective view of one of the details.

Fig. 5 is a detail sectional view of one of the eye-studs.

Referring now more particularly to the several views of the drawing, it will be apparent that, the window seat of the present invention will include a seat or platform 10 having a frame 11 connected as at 12 to what will be the rear end of the seat 10 and connected to the frame 11 and at the opposite sides of the seat 10 respectively are strips 13 of webbing or the like. The frame 11 and the strips 13 constitute a means for preventing a person from slipping backward on the seat 10 beyond a certain point. In order to detachably connect the seat to a portion of the window frame, preferably the window sill, there are provided eye-studs 14 and hooks 15 at the front end of the seat 10. Each of the eye-studs 14 will be screwed into the sill 16. Each of the eye-studs 14 at the juncture between the eye and the screw threaded part is concaved as at 17 so that

each stud will effectively bite into the sill and thus prevent accidental turning. The hooks 15 are embodied by rods 18, each of which is disposed in a groove 19 in the under side of the seat 10, with one upturned end 20 in a hole in the seat to prevent longitudinal movement, there being a plate 21 provided which is attached to the under side of the seat 10 to prevent downward movement of the rods. The hooks 15 are spaced apart one at each side of the seat 10 at the front end thereof, and the eye-studs 14 are similarly spaced so that the hooks 15 will be receivable respectively in the eyes of the eye-studs 14. In order to maintain the hooks 15 in the eyes of the studs 14, to hold the seat 10 effectively in place against movement, and to maintain the seat 10 in any desired position of adjustment, there are provided extensible devices 22 or turnbuckles 22 and 23, the turnbuckle 22 being shorter than the turnbuckle 23. The turnbuckles 22 and 23 are arranged in pairs, one pair at each side of the seat 10. Associated with each pair of turnbuckles is a base or foot 24 to which each of the turnbuckles is pivotally connected as at 25 and 26, and the opposite ends of the turnbuckles are pivotally connected respectively as at 27 and 28 to the under side of the seat 10. It will be apparent that the turnbuckles of each pair bear a converging relationship with respect to each other as connected to the foot 24. By manipulating the turnbuckles it is possible to adjust the foot 24 of each pair to the desired disposition and in actual practice each foot will rest on the outside sill 29 and will butt against one edge of the sill 16 of the window frame, as shown most clearly in Fig. 2. Under such arrangement the seat will be prevented from moving relatively to the window frame, and all possibility of accidental disconnection of the hooks 15 with the eyes of the studs 14 will be eliminated. It will be apparent that by adjusting the turnbuckles 22 and 23, the seat 10 may be disposed in different positions, the adjustable feature being illustrated in Fig. 2 in which the seat is shown in dotted lines in Fig. 2. The seat may be readily detached by adjusting the turnbuckles 22 and 23 until the foot of each pair is so disposed that the hooks 15 may be readily disengaged. The seat 10 is provided with a removable part 30 which gives access to the turnbuckles 22 and 23 when the window seat is arranged on the window frame, so that further ad-

justment of the turnbuckles may be made in a convenient manner from the inside.

I claim:

1. A window seat comprising a platform, and means for effecting the detachable connection of the platform, said means comprising a pair of turnbuckles at each side of the platform, each turnbuckle pivotally connected to the platform, one turnbuckle of each pair being longer than the other turnbuckle, a base member associated with each pair of turnbuckles, to which the lower end of each of the turnbuckles is pivotally connected, and the longer turnbuckle of each pair disposed behind the shorter turnbuckle.

2. A window seat comprising a platform, and means for effecting the attachment of the platform, said means comprising turnbuckles pivotally connected to the platform, each of the turnbuckles extending downwardly and forwardly with respect to the platform, a foot member, each of said turnbuckles being connected pivotally to said foot member, one turnbuckle being shorter than the other and arranged forwardly of the latter, hooks on the platform, and eye-studs which are adapted to coact with the hooks.

EUGENE SONNTAG.
